TOILET TANK BALLOCOCK OR THE LIKE

Harry W. Hudson, Littleton, Colo., assignor to Twentieth Century Products Corp., Englewood, Colo.

Filed Feb. 1, 1968, Ser. No. 10,399

Term of patent 14 years

Int. Cl. D23—01

U.S. Cl. D23—40

FIG. 1 is a side elevational view of a toilet tank ballcock or the like, showing my new design therefor, the opposite side being essentially the same as the side shown;

FIG. 2 is a side elevational view thereof, oriented 90° relative to FIG. 1, the opposite side being essentially the same as the side shown;

FIG. 3 is a top plan view thereof, oriented as seen in FIG. 1; and

FIG. 4 is a bottom plan view thereof, oriented as seen in FIG. 2.

I claim:

The ornamental design for a toilet tank ballcock or the like, substantially as shown and described.
